RAILWAY BRAKING APPARATUS

Delbert F. Cobourn, Portsmouth, Ohio, assignor
to The Union Switch & Signal Company, Swiss-
vale, Pa., a corporation of Pennsylvania

Application May 26, 1936, Serial No. 81,888

8 Claims. (Cl. 303—20)

My invention relates to railway braking apparatus, and particularly to braking apparatus of the type comprising a braking bar located in the trackway and actuated by a fluid pressure motor controlled from a remote point. More particularly, my present invention relates to improvements in braking apparatus of the type described and claimed in Letters Patent of the United States No. 1,888,548, granted to H. L. Bone and J. W. Livingston, on November 22, 1932.

I will describe one form of braking apparatus embodying my invention, and will then point out the novel features thereof in claims.

The accompanying drawing is a view, partly diagrammatic, illustrating one form of railway braking apparatus embodying my invention.

Referring to the drawing, the reference characters 1 and 1^a designate the track rails of a stretch of railway track. Located on opposite sides of rail 1, and extending parallel therewith, are two braking bars 2 and 3. Two similar braking bars 2^a and 3^a extend parallel with rail 1^a on opposite sides thereof.

The braking bars 2, 3, 2^a, and 3^a are operated by a fluid pressure motor M, which, in the form here shown, comprises a cylinder 4 containing an auxiliary piston 6 which is movable between the left-hand end of the cylinder and an intermediate point in the cylinder, and a main piston 5 which is movable between a retracted position at the right-hand end of the cylinder and a projected position where it engages the auxiliary piston 6. It will be plain, therefore, that when the auxiliary piston 6 occupies its projected position, in which position it is illustrated in the drawing, the stroke of the main piston 5 is less than when the auxiliary piston 6 occupies its retracted position. The sealing ring of the auxiliary piston 6 is located at 6^a in the drawing, and the parts are so proportioned that even when the auxiliary piston occupies its projected position, it does not blank a pipe 28 which communicates with the cylinder 4. Piston 6 is provided with flutes or holes by means of which the pipe 28 may at all times communicate with the regions between pistons 5 and 6. The main piston 5 of motor M is attached to a piston rod 7, which piston rod, in turn, is operatively connected with the braking bars 2, 3, 2^a, and 3^a by means of suitable operating mechanism, one form of which I will now describe.

As here shown, this operating mechanism comprises a link 8 which is connected at one end to the free end of the piston rod 7, and at the other end to one arm of a three-arm lever 9 which is pivotally supported in the trackway at 10. The

second arm of the lever 9 is connected, through a link 11, with a crank 12 which is pivotally supported in the trackway at 13; and a third arm of lever 9 is connected, through a link 14, with a crank 15 which is pivotally supported in the trackway at 16. It will be seen, therefore, that the links 11 and 14 and the lever 9 constitute a toggle by means of which the cranks 12 and 15 may be swung in the same directions when the main piston 5 of motor M is operated. The free end of crank 12 is operatively connected with the braking bars 2 and 2^a, respectively, by means of resilient connections which include springs 17 and 18; and, similarly, the free end of the crank 15 is operatively connected with the braking bars 3 and 3^a by means of resilient connections which include springs 19 and 20. It will be seen, therefore, that when piston 5 moves toward the left, the cranks 12 and 15 are both swung in a clockwise direction, so that each braking bar is moved toward the associated rail into a braking position in which it engages the sides of a wheel of a railway car traversing the rails 1 and 1^a. When the piston 5 moves toward the right, however, the cranks 12 and 15 are both swung in a counter-clockwise direction, and the braking bars are moved away from the associated rails to their non-braking positions, in which they are out of engagement with the wheels of a passing car. One form of operating mechanism of the type described is disclosed and claimed in Letters Patent of the United States No. 1,812,191, granted to H. L. Bone, on June 30, 1931, for Railway braking apparatus.

The motor M is controlled by four magnet valves V¹, V², V³, and V⁴. As here shown, each valve V comprises a valve stem 21, biased to an upper position by a spring 22, and provided with an armature 23 and a winding 24. When valve V¹ is energized, valve stem 21 of this valve moves downwardly against the bias exerted by spring 22, as shown in the drawing, and a pipe 26, which communicates with the left-hand end of cylinder 4, is then connected with a pipe 25 which is constantly supplied with fluid pressure, usually air, from a suitable source not shown in the drawing. When valve V¹ is deenergized, however, valve stem 21 is moved upwardly by spring 22, and pipe 26 is then disconnected from pipe 25. When valve V² is energized, valve stem 21 of this valve moves downwardly, thereby connecting pipe 26 with pipe 28, but when valve V² is deenergized, pipe 26 is disconnected from pipe 28. When valve V³ is energized, a pipe 29 which communicates with the right-hand end of cylinder 4 is vented

10

45

50

55

to atmosphere through a port 27; but when valve V³ is deenergized, pipe 29 is disconnected from atmosphere, and pipe 28 which is disconnected from port 27 when this valve is energized, is then connected with port 27. When valve V⁴ is energized, valve stem 21 of this valve moves downwardly and connects pipe 29 with pipe 25, but when valve V⁴ is deenergized, pipe 29 is disconnected from pipe 25.

The valves V are controlled in part by a plurality of pressure responsive devices, each designated by the reference character P with a distinguishing exponent. Referring to the pressure responsive device P³⁰, for example, this device comprises a Bourdon tube 44 connected by means of a pipe 31 with pipe 28, and so subjected at all times to the pressure in the middle of cylinder 4. The Bourdon tube 44 controls a contact 45-45^a which is closed at all times except when the pressure exceeds a predetermined value which is just sufficient to move the braking apparatus to its open position. For example, this pressure might be 30 pounds per square inch. The pressure responsive devices P¹⁰⁻²⁰ and P⁴⁰⁻⁵⁰ are similar to the pressure responsive device P³⁰, except that the Bourdon tubes 44 of these devices are connected to a pipe 30 which enters cylinder 4 at such a point that these tubes will be subjected to the pressure in the region between the pistons 5 and 6 until piston 5 has moved toward the left just far enough to move the braking bars to their braking positions, after which these tubes will then be subjected to the pressure in the region between the main piston 5 and the right-hand end of the cylinder. That is to say, devices P¹⁰⁻²⁰ and P⁴⁰⁻⁵⁰ are responsive to the pressure in front of piston 5 when the piston is in its retracted position, and to the pressure behind the piston when the latter is in its projected position. The pressure responsive devices P¹⁰⁻²⁰ and P⁴⁰⁻⁵⁰ are arranged to operate successively, as the pressure to which these devices are subjected is increased. For example, for all pressures below 10 pounds per square inch, contact 45-45^a of each of these devices is closed. If the pressure exceeds 10 pounds per square inch, however, contact 45-45^a of device P¹⁰⁻²⁰ opens, and if the pressure exceeds 20 pounds per square inch, contact 45-45^b of device P¹⁰⁻²⁰ closes. In a similar manner, the pressure responsive device P⁴⁰⁻⁵⁰ is adjusted to open its contact 45-45^a at 40 pounds per square inch and to close its contact 45-45^b at 50 pounds per square inch. The pressure responsive device P⁵⁻¹⁰ is likewise similar to the pressure responsive device P³⁰, and is connected to the same pipe 31 to which the device P³⁰ is connected. The contacts 45-45^a and 45-45^b of this latter pressure responsive device are so adjusted, however, that the contact 45-45^a will become opened when the pressure in the middle of cylinder 4 exceeds 5 pounds per square inch, and the contact 45-45^b will become closed when the pressure in the middle of cylinder 4 exceeds 10 pounds per square inch. It should be pointed out that the specific pressures mentioned for the opening and closing of the contacts of the pressure responsive devices P are given merely by way of illustration, and may be varied as operating conditions require.

The valves V are further controlled by means of a manually operable lever L which, as here shown, is capable of assuming six positions indicated by dotted lines in the drawing, and designated by the reference characters p⁰, p¹, p², p³, p⁴, and p⁵. The lever L controls a plurality of

contacts 33-34, 35-36, 37-38, 39-40, 41-42, 41-43, 46-47, and 46-48. Contacts 41-42 and 46-47 are closed only when lever L occupies its p⁰ position; contact 33-34 is closed when lever L occupies its p⁰ position, its p¹ position, or any position intermediate these two positions; contact 35-36 is closed only when lever L occupies its p² position; contact 37-38 is closed only when lever L occupies its p³ position; contact 39-40 is closed when lever L occupies its p⁴ position, its p⁵ position, or any position intermediate these two positions; contact 41-43 is closed only when lever L occupies its p⁵ position; and contact 46-48 is closed when lever L occupies its p² position, its p³ position, its p⁴ position, or any position intermediate these three positions.

The lever L will usually be located at a point remote from the braking apparatus, as in the control cabin of a classification yard car retarder system, and will be connected with the braking apparatus by means of line wires extending from the control cabin to the braking apparatus.

As shown in the drawing, lever L occupies its p⁰ or "off" position. A circuit is therefore completed for valve V³ at contact 33-34 of lever L, and current flows from a suitable source here shown as a battery B through wires 49 and 50, contact 33-34 of lever L, line wire 51, an asymmetric unit 52 in its low resistance direction, the winding 24 of valve V³, and common line wire 53 back to battery B. Valve V³ is therefore energized so that the right-hand end of cylinder 4 is connected with atmosphere at port 27. With lever L in its p⁰ position, a circuit is also completed for valve V² at contact 41-42 of lever L, and current flows from battery B through wire 49, contact 41-42 of lever L, wire 54, line wire 55, an asymmetric unit 56 in its low resistance direction, winding 24 of valve V², and line wire 53 back to battery B. Valve V² is therefore also energized, so that pipe 26 is connected with pipe 28. Furthermore, with lever L in its p⁰ position, if the pressure in the region of cylinder 4 between the pistons 5 and 6 is below 30 pounds per square inch, a circuit will also be completed for valve V¹, which circuit passes from battery B through contact 46-47 of lever L, line wire 57, contact 45-45^a of pressure responsive device P³⁰, wire 58, the winding 24 of valve V¹, and wire 53 back to battery B. Valve V¹ will therefore become energized and will connect pipe 26 with pipe 25. When pipe 26 becomes connected with pipe 25 under these conditions, fluid pressure will be admitted to the left-hand end of cylinder 4, and also to the region between the pistons 5 and 6, until the pressure in these regions exceeds 30 pounds per square inch, at which time contact 45-45^a of pressure responsive device P³⁰ will open and will deenergize valve V¹. All circuits for valve V⁴ are open and this valve is therefore deenergized. It will be seen, therefore, that when lever L occupies its p⁰ position, piston 5 of motor M is held in its extreme right-hand position in cylinder 4 by a pressure of 30 pounds per square inch, and the braking bars therefore occupy their retracted or ineffective positions. Since the piston 5 occupies its extreme right-hand position, the Bourdon tubes 44 of the pressure responsive devices P¹⁰⁻²⁰ and P⁴⁰⁻⁵⁰ are subjected to the pressure in the region of cylinder 4 between the pistons 5 and 6. Contact 45-45^b of device P¹⁰⁻²⁰ and contact 45-45^a of device P⁴⁰⁻⁵⁰ are therefore both closed, while contact 45-45^a of pressure responsive device P¹⁰⁻²⁰ and contact 45-45^b of device P⁴⁰⁻⁵⁰ 75

are therefore open. Furthermore, since pipe 28 is constantly subjected to the pressure in the region of cylinder 4 between the pistons 5 and 6, and since the pressure in this region is maintained at 30 pounds per square inch under these conditions, contact 45-45^a of pressure responsive device P⁵⁻¹⁰ is open and contact 45-45^b of this device is closed.

In explaining the operation of the apparatus as a whole, I will first assume that the operator wishes to make a comparatively light brake application. To do this, he will move lever L from its p⁰ to its p² position. This movement of lever L will open contacts 33-34 and 41-42 of the lever, and will thus interrupt the circuits which were previously closed for valves V³ and V², so that these valves will both become deenergized. The deenergization of valve V³ will disconnect pipe 29 from port 27 and will connect pipe 28 with port 27, thereby preventing the escape of fluid from the region of cylinder 4 on the right-hand side of piston 5, and permitting fluid to escape from the region of cylinder 4 between the pistons 5 and 6; while the deenergization of valve V² will disconnect pipe 26 from pipe 28, thus preventing the fluid which was previously supplied to cylinder 4, to hold auxiliary piston 6 in its projected position, from escaping through port 27. The movement of lever L to its p² position also opens contact 46-47 of the lever and closes contacts 35-36 and 46-48. When contact 46-47 becomes opened, it interrupts the previously traced circuit for valve V¹, and if the circuit for this valve is not already open at contact 45-45^a of pressure responsive device P³⁰, as will be the case if the pressure of the fluid in the region of cylinder 4 between the pistons 5 and 6 at the instant lever L is moved to its p² position is above 30 pounds per square inch, valve V¹ will become deenergized and will cut off the supply of fluid to the left-hand end of cylinder 4. If, however, valve V¹ is already deenergized, the opening of contact 46-47 of lever L will, of course, have no effect on valve V¹. Valve V¹, however, will not long remain deenergized under these conditions because when contact 46-48 of lever L and contact 45-45^a of pressure responsive device P³⁰ are both closed, another circuit is completed for valve V¹, which circuit is similar to the previously traced circuit for this valve with the exception that this other circuit includes contact 46-48 of lever L in place of contact 46-47; and, if contact 45-45^a of pressure responsive device P³⁰ is not closed when contact 46-48 becomes closed, the pressure in the region of cylinder 4 between pistons 5 and 6 will soon decrease sufficiently to permit this contact to become closed. The energization of valve V¹ will, of course, cause fluid at full line pressure to be admitted to the left-hand end of cylinder 4, which fluid will hold auxiliary piston 6 in its projected position in which it is shown in the drawing. When contact 35-36 of lever L becomes closed, the pressure of the fluid in the region of cylinder 4 between the pistons 5 and 6 will still be sufficiently high, so that contact 45-45^b of pressure responsive device P¹⁰⁻²⁰ and contact 45-45^b of pressure responsive device P⁵⁻¹⁰ will both be closed, and, as a result, the closing of contact 35-36 will complete a circuit for valve V⁴, which circuit may be traced from a battery C through line wire 53, winding 24 of valve V⁴, wire 60, an asymmetric unit 61 in its low resistance direction, contact 45-45^b of pressure responsive device P⁵⁻¹⁰, wire 62, contact 45-45^b of pressure responsive device P¹⁰⁻²⁰, wire 63, line

wire 51, contact 35-36 of lever L, and wires 64 and 65 back to battery C. Valve V⁴ will therefore become energized and will connect pipe 29 with pipe 25, thus causing fluid at full line pressure to be supplied to the right-hand end of cylinder 4. This pressure will drive piston 5 toward the left, thereby moving the braking bars toward their braking positions. When piston 5 has been moved toward the left to the position in which the braking bars will just engage the wheels of a car passing through the braking apparatus, Bourdon tubes 44 of the pressure responsive devices P¹⁰⁻²⁰ and P⁴⁰⁻⁵⁰ will become subjected to the pressure in the right-hand end of the cylinder, and due to the fact that full line pressure is admitted to cylinder 4 to move the braking bars toward their braking positions, the piston 5 will probably reach this position before the pressure of the fluid in the region of cylinder 4 between the pistons 5 and 6 has decreased to the pressure at which the contact 45-45^b of either one of the pressure responsive devices P¹⁰⁻²⁰ or P⁵⁻¹⁰ becomes opened. It follows, therefore, that while the braking bars are being moved to their braking positions, the circuit for valve V⁴ will probably remain closed. However, if the fluid in the region of cylinder 4 between the pistons 5 and 6 should become vented to atmosphere at a sufficiently rapid rate to permit the contact 45-45^b of either of the pressure responsive devices P¹⁰⁻²⁰ or P⁵⁻¹⁰ to open and deenergize valve V⁴ before the braking bars reach their full braking positions, thus causing the supply of fluid pressure to the right-hand end of cylinder 4 to become cut off, the expansion of the fluid previously supplied to this end of the cylinder will complete the movement of the braking bars. When the piston 5 reaches the position in which the Bourdon tubes 44 of the pressure responsive devices P¹⁰⁻²⁰ and P⁴⁰⁻⁵⁰ become subjected to the pressure of the fluid in the right-hand end of cylinder 4, if contact 45-45^b of device P¹⁰⁻²⁰ has become opened, this contact will immediately become closed, and if the contact is still closed, it will remain closed at least temporarily. Furthermore, contact 45-45^a of pressure responsive device P⁴⁰⁻⁵⁰ will become open, and contact 45-45^b of device P⁴⁰⁻⁵⁰ will become closed. The operation of the contacts 45-45^a and 45-45^b of the pressure responsive device P⁴⁰⁻⁵⁰ under these conditions, however, will have no effect on the remainder of the apparatus. As soon as the pressure in the region of cylinder 4 between the pistons 5 and 6 has decreased to the pressure at which contact 45-45^b of pressure responsive device P⁵⁻¹⁰ becomes opened, if valve V⁴ has not already become deenergized, this valve will become deenergized and will cut off the supply of fluid pressure to the right-hand end of cylinder 4, and when the pressure in the region of cylinder 4 between the pistons 5 and 6 has decreased to the pressure at which contact 45-45^a of pressure responsive device P⁵⁻¹⁰ becomes closed, a circuit will become completed for valve V³ passing from battery C through wire 53, the winding 24 of valve V³, wire 66, contact 45-45^a of pressure responsive device P⁵⁻¹⁰, wire 62, contact 45-45^b of pressure responsive device P¹⁰⁻²⁰, wire 63, line wire 51, contact 35-36 of lever L, and wires 64 and 65 back to battery C. Valve V³ will therefore become energized, and will vent fluid from the right-hand end of cylinder 4 until the pressure of the fluid in this end of the cylinder decreases to 20 pounds per square inch, at which time contact 45-45^b of pressure responsive de-

vice P^{10-20} will open and will deenergize valve V^3 , thus preventing the further escape of fluid from the right-hand end of cylinder 4. If the pressure in the right-hand end of cylinder 4 decreases below 10 pounds per square inch for any reason, contact 45-45^a of pressure responsive device P^{10-20} will become closed and will complete another circuit for valve V^4 passing from battery C through line wire 53, winding 24 of valve V^4 , wire 60, asymmetric unit 61 in its low resistance direction, wire 67, contact 45-45^a of pressure responsive device P^{10-20} , wire 63, line wire 51, contact 35-36 of lever L, and wires 64 and 65 back to battery C. Valve V^4 will therefore again become energized, and will again admit fluid pressure to the right-hand end of cylinder 4 until the pressure builds up to a pressure of 10 pounds per square inch, at which time contact 45-45^a of device P^{10-20} will open and will deenergize valve V^4 . It will be apparent, of course, that as soon as the pressure of the fluid in the right-hand end of cylinder 4 decreases below 50 pounds per square inch, contact 45-45^b of device P^{40-50} will open, and that as soon as the pressure in the right-hand end of cylinder 4 decreases below 40 pounds per square inch, contact 45-45^a of pressure responsive device P^{40-50} will become closed. The operation of the contacts 45-45^a and 45-45^b of pressure responsive device P^{40-50} under these conditions, however, will have no effect on the remainder of the apparatus. It will be seen, therefore, that when lever L occupies its p^2 position, piston 5 is urged toward the left by a pressure of between 10 and 20 pounds per square inch. The movement of piston 5 toward the left under these conditions is limited by the auxiliary piston 6, which as pointed out hereinbefore, is held in its projected position by fluid at full line pressure, and the parts are so proportioned that the movement of lever 9 caused by this movement of piston 5 does not bring the toggle of which lever 9 forms a part, to its dead center position. It follows, therefore, that when a car enters the braking apparatus, the braking bars may be forced away from the rails, thereby transmitting the reaction of the wheels through the operating mechanism to the piston 5. As a result, the piston 5 may be moved slightly toward the right, thereby cushioning the braking action of the braking apparatus against the volume of air in cylinder 4.

If the operator desires to make a more powerful brake application, he will move lever L to its p^3 position. If, when he does this, the lever previously occupied its p^0 position in which it is shown in the drawing, the operation of the apparatus will then be similar to that just described with the following exceptions. Valve V^4 will now initially become energized over a circuit which passes from battery C through line wire 53, winding 24 of valve V^4 , wire 60, asymmetric unit 61 in its low resistance direction, wire 67, contact 45-45^a of pressure responsive device P^{40-50} , wire 68, an asymmetric unit 69 in its low resistance direction, line wire 55, contact 37-38 of lever L, and wires 64 and 65 back to battery C. When piston 5 has moved toward the left to the position in which the pressure responsive devices P^{10-20} and P^{40-50} become subjected to the pressure of the fluid in the right-hand end of cylinder 4, contact 45-45^a of pressure responsive device P^{40-50} will open and contact 45-45^b of this pressure responsive device will become closed. The opening of contact 45-45^a of pressure responsive device P^{40-50} will interrupt the circuit which was previously closed for valve V^4 , and if contact

45-45^b of pressure responsive device P^{5-10} is then closed, another circuit for valve V^4 will become completed which circuit may be traced from battery C through line wire 53, winding 24 of valve V^4 , wire 60, asymmetric unit 61 in its low resistance direction, contact 45-45^b of pressure responsive device P^{5-10} , contact 45-45^b of pressure responsive device P^{40-50} , wire 68, asymmetric unit 69 in its low resistance direction, line wire 55, contact 37-38 of lever L, and wires 64 and 65 back to battery C. If, however, contact 45-45^a of pressure responsive device P^{5-10} is closed when contact 45-45^b of pressure responsive device P^{40-50} becomes opened, all circuits for valve V^4 will then be open, and a circuit for valve V^3 will become closed which latter circuit may be traced from battery C through line wire 53, the winding 24 of valve V^3 , wire 66, contact 45-45^a of pressure responsive device P^{5-10} , contact 45-45^b of pressure responsive device P^{40-50} , wire 68, asymmetric unit 69 in its low resistance direction, line wire 55, contact 37-38 of lever L, and wires 64 and 65 to battery C. Valve V^4 will therefore become deenergized and will cut off the supply of fluid pressure to the right-hand end of cylinder 4, and valve V^3 will become energized and will vent fluid from the right-hand end of cylinder 4. The valve V^3 will continue to vent fluid from the right-hand end of cylinder 4 until the pressure of the fluid in this end of the cylinder decreases to 50 pounds per square inch, at which time contact 45-45^b of pressure responsive device P^{40-50} will open and will deenergize this valve. If the pressure in the right-hand end of cylinder 4 now decreases below 40 pounds per square inch, contact 45-45^a of pressure responsive device P^{40-50} will again become closed and will complete the previously traced circuit for valve V^4 . Valve V^4 will therefore again become energized and will admit fluid pressure to the right-hand end of cylinder 4 until the pressure increases to 40 pounds per square inch at which time contact 45-45^a of pressure responsive device P^{40-50} will open and will deenergize valve V^4 . It will be apparent, therefore, that when lever L occupies its p^3 position, the piston 5 is forced toward the left-hand end of cylinder 4, and is held against auxiliary piston 6, by a fluid at a pressure of between 40 and 50 pounds per square inch.

If, when lever L is moved to its p^3 position to increase the braking force, the lever had previously occupied its p^2 position, piston 5 will already be moved to the left to the position in which the Bourdon tubes 44 of the pressure responsive devices P^{10-20} and P^{40-50} are subjected to the pressure of the fluid in the right-hand end of cylinder 4, and the fluid in the region of cylinder 4 between pistons 5 and 6 will already be at atmospheric pressure so that contact 45-45^a of device P^{5-10} will be closed and contact 45-45^b of this device will be open. As a result, valve V^4 will initially become energized over the same circuit as when lever L is moved to its p^3 position from its p^0 position, but as soon as the pressure in the right-hand end of cylinder 4 has increased to 40 pounds per square inch, this valve will immediately become deenergized. After this valve once becomes deenergized, the valves V^4 and V^3 will then operate to maintain the fluid in the right-hand end of cylinder 4 at a pressure of between 40 and 50 pounds per square inch in a manner which will be readily understood from an inspection of the drawing, and from the foregoing description, without further detailed description.

If the operator moves lever L to its p^4 position,

a circuit will be completed for valve V^4 passing from battery C through wire 53, winding 24 of valve V^4 , wire 60, line wire 70, contact 39-40 of lever L, and wire 65 back to battery C. Valve V^4 will therefore become energized and will admit fluid pressure to the right-hand end of cylinder 4 to move piston 5 toward the left in the manner previously described. Under these conditions, piston 6 will be held in its projected position by virtue of the circuit previously described for valve V^1 including contact 46-48 of lever L, so that the movement of piston 5 toward the left will be arrested when it engages the auxiliary piston 6. The circuit over which valve V^4 becomes energized under these conditions remains continuously closed, and it will be apparent, therefore, that piston 5 will now be held in the position in which it engages the auxiliary piston 6 by fluid at full line pressure.

If it is desirable to apply a still higher braking force, the operator will move lever L to its p^5 position, thereby opening contact 46-48 of lever L and closing contact 41-43 of lever L. When contact 46-48 becomes opened, the circuit previously traced for valve V^1 including this contact becomes interrupted and valve V^1 therefore becomes deenergized, so that the supply of fluid pressure to the left-hand end of cylinder 4 is cut off. When contact 41-43 of lever L becomes closed, a circuit is completed for valve V^2 which is similar to the circuit previously traced for this valve except that this latter circuit includes contact 41-43 of lever L in place of contact 41-42 of lever L. Valve V^2 therefore becomes energized, and since all circuits for valve V^3 are now open, so that valve V^3 is deenergized, the left-hand end of cylinder 4 is vented to atmosphere. Furthermore, since contact 39-40 of lever L is closed under these conditions, the previously traced circuit for valve V^4 including this contact is closed, and valve V^4 is therefore also energized. Fluid at full line pressure is therefore admitted to the right-hand end of cylinder 4 in the manner previously described, and since the left-hand end of cylinder 4 is now vented to atmosphere, this pressure moves the pistons 5 and 6 to the extreme left-hand end of the cylinder. It will be apparent, therefore, that under these conditions, piston 5 will be held in its extreme left-hand position by fluid at full line pressure. The parts are so proportioned that when piston 5 occupies this position, lever 9 occupies the position in which the toggle of which it forms a part is nearly on dead center. When the parts occupy these positions, the reaction of ordinary car wheels is not sufficient to move the toggle mechanism, and the entire forces exerted by the springs 17, 18, 19, and 20 of the resilient connections are available to hold the braking bars against the wheels of the car.

It should be observed that if the operator moves lever L from a position corresponding to a higher braking force to a position corresponding to a lower braking force, the apparatus will immediately and automatically reduce the braking force to a value corresponding to the new position of the lever for reasons which will be apparent from the drawing without tracing the operation in detail.

In order to restore the apparatus from its closed or effective position to its open or ineffective position, the operator moves lever L to its p^0 position in which it is illustrated in the drawing. The closing of contacts 33-34, 41-42, and 46-47 of lever L under these conditions completes the circuits previously traced for valves V^1 , V^2 , and V^3 , and these valves therefore all now become energized. The energization of valve V^1 admits fluid pressure to the left-hand end of cylinder 4 so that the auxiliary piston 6 is moved to its projected position in which it is illustrated in the drawing. The energization of valve V^2 connects pipe 26 with pipe 28, and since valve V^1 is energized so that pipe 26 is supplied with fluid pressure, fluid pressure is then admitted to the region between the pistons 5 and 6. The energization of valve V^3 disconnects pipe 28 from atmosphere and connects pipe 29 with atmosphere. When pipe 29 becomes connected with atmosphere, the pressure in the right-hand end of cylinder 4 becomes exhausted, and the pressure between the pistons 5 and 6 therefore moves piston 5 toward the right to restore the braking apparatus to its open or ineffective position in which it is illustrated in the drawing. If the pressure in the region of cylinder 4 between the pistons 5 and 6 exceeds 30 pounds per square inch during the movement of piston 5 toward the right, contact 45-45^a of pressure responsive device P³⁰ will open as previously described, and will interrupt the circuit for valve V^1 including this contact. Valve V^1 will, therefore, become deenergized, and will cut off the supply of fluid pressure to the region of cylinder 4 between the auxiliary piston and the adjacent end of the cylinder and between the pistons 5 and 6. When the pressure has again dropped below 30 pounds per square inch, contact 45-45^a of pressure responsive device P³⁰ will again become closed to restore the circuit for valve V^1 . It will be seen, therefore, that piston 5 is moved to its right-hand position, and is subsequently maintained in this position, by a pressure of 30 pounds per square inch. This pressure will cause contact 45-45^b of pressure responsive device P¹⁰⁻²⁰ to become closed, and will also cause contact 45-45^b of pressure responsive device P⁵⁻¹⁰ to become closed. When the piston 5 reaches its right-hand position, the parts will all be restored to their normal conditions in which they are shown in the drawing.

If, after the parts have been restored to their normal positions in which they are shown in the drawing, it is not desired to immediately use the retarder, the operator will then move lever L to its p^1 or "exhaust" position. This movement of the lever will interrupt the circuits which were previously closed for the valves V^1 and V^2 , thus causing these valves to become deenergized. The circuit for valve V^3 , however, will remain closed and this valve will therefore remain energized. With valves V^1 and V^2 deenergized and valve V^3 energized, the supply of fluid pressure to the region of cylinder 4 between the auxiliary piston 6 and the left-hand end of the cylinder and between the pistons 5 and 6 will become cut off, and the fluid which was previously supplied to these regions of the cylinder will become trapped in the cylinder, thus causing the braking bars to be held in their non-braking positions. It should be noted, however, that since the valves V^1 and V^2 are both deenergized, the amount of electrical energy consumed by the braking apparatus under these conditions will be considerably less than if the lever were allowed to remain in its p^0 or "off" position.

It should be pointed out that the functions of the rectifiers 52, 56, 61, and 69 is to permit certain ones of the line wires to be used in more than one circuit without causing improper energization of the valves V, whereby the number of line

wires required to effect the desired operating functions is reduced to a minimum.

Although I have herein shown and described only one form of railway braking apparatus embodying my invention, it is understood that various changes and modifications may be made therein within the scope of the appended claims without departing from the spirit and scope of my invention.

10 Having thus described my invention, what I claim is:

1. Railway braking apparatus comprising a cylinder, a piston movable therein having a retracted and a projected position, means for at times admitting fluid pressure to said cylinder in front of said piston to move it to its retracted position, two magnet valves, means controlled by the one valve for admitting fluid pressure behind said piston to move it to its projected position, means controlled by the other valve for exhausting fluid pressure from behind said piston, pressure responsive means connected with said cylinder at such point as to be subjected to the pressure behind said piston when and only when said piston has been moved away from its retracted position more than a predetermined distance, other fluid pressure responsive means connected with said cylinder at such point as to be constantly subjected to the pressure in front of said piston, means controlled by said two pressure responsive means for selectively controlling said two valves, and car retarding means operated by said piston.

2. Railway braking apparatus comprising a cylinder, a piston movable therein having a retracted and a projected position, means for at times admitting fluid pressure to said cylinder in front of said piston to move it to its retracted position, two magnet valves, means controlled by the one valve for admitting fluid pressure behind said piston to move it to its projected position, means controlled by the other valve for exhausting fluid pressure from behind said piston, pressure responsive means connected with said cylinder at such point as to be subjected to the pressure behind said piston when and only when said piston has been moved away from its retracted position more than a predetermined distance, other fluid pressure responsive means connected with said cylinder at such point as to be constantly subjected to the pressure in front of said piston, a manually operable lever movable to different positions, means controlled by said lever and by said two pressure responsive means for selectively controlling said two valves, and car retarding means operated by said piston.

3. Railway braking apparatus comprising a cylinder, a piston movable therein having a retracted and a projected position, means for at times admitting fluid to said cylinder in front of said piston to move it to its retracted position, a first magnet valve effective when energized for admitting fluid pressure behind said piston to move it to its projected position, a second magnet valve effective for exhausting fluid from behind or in front of said piston according as said valve is energized or deenergized, a first fluid pressure responsive device constantly subjected to the pressure of the fluid in front of said piston and a second fluid pressure responsive device at times subjected to the pressure of the fluid in front of said piston and at other times to the pressure behind said piston depending upon the position of said piston, means controlled by said two fluid pressure responsive devices for selectively con-

trolling said valves, and car retarding means operated by said piston.

4. Railway braking apparatus comprising a cylinder, a piston movable therein having a retracted and a projected position, means for at times admitting fluid to said cylinder in front of said piston to move it to its retracted position, a first magnet valve effective when energized for admitting fluid behind said piston to move it to its projected position, a second magnet valve effective for exhausting fluid from behind or in front of said piston according as said valve is energized or deenergized, a first fluid pressure responsive device constantly subjected to the pressure of the fluid in front of said piston and a second fluid pressure responsive device at times subjected to the pressure of the fluid in front of said piston and at other times to the pressure behind said piston depending upon the position of said piston, a manually operable lever, means controlled by said lever and by said two fluid pressure responsive devices for selectively controlling said valves, and car retarding means operated by said piston.

5. Railway braking apparatus comprising a cylinder, a piston movable therein having a retracted and a projected position, a first magnet valve for controlling the admission of fluid pressure to said cylinder on one side of said piston, a second magnet valve for controlling the admission of fluid to said cylinder on the other side of said piston, a third magnet valve for controlling the exhaust of fluid from said cylinder on both sides of said piston, a first fluid pressure responsive device constantly subjected to the pressure of the fluid in said cylinder on one side of said piston, a second fluid pressure responsive device connected with said cylinder at such point that said second device will at times be subjected to the pressure of the fluid on one side of said piston and at other times to the pressure of the fluid on the other side of said piston, a manually operable lever, means controlled by said lever for controlling said first valve, means controlled jointly by said lever and by said two pressure responsive devices for selectively controlling said second and third valves, and car retarding means controlled by said piston.

6. Railway braking apparatus comprising a cylinder, a piston movable therein having a retracted and a projected position, a first magnet valve effective when energized for admitting fluid pressure in front of said piston to move it to its retracted position, a second magnet valve effective when energized for admitting fluid pressure behind said piston to move it to its projected position, a third magnet valve for exhausting fluid pressure from in front of said piston or behind said piston according as said third valve is deenergized or energized, a first pressure responsive device connected with said cylinder at such point as to be subjected to the pressure in front of said piston when the piston is in its retracted position and to the pressure behind said piston when the piston has been moved away from its retracted position more than a predetermined distance, a second pressure responsive device connected with said cylinder at such point as to be constantly subjected to the pressure in front of said piston, contacts controlled by said pressure responsive devices, a manually operable lever, means controlled by said lever for at times energizing said first magnet valve, other means controlled by said lever and by said contacts for selectively energizing said second and third magnet valves, and car retarding means operated by said piston.

7. Railway braking apparatus comprising a cylinder, a piston movable therein having a retracted and a projected position, a first magnet valve effective when energized for admitting fluid pressure in front of said piston to move it to its retracted position, a second magnet valve effective when energized for admitting fluid pressure behind said piston to move it to its projected position, a third magnet valve for exhausting fluid pressure from in front of said piston or behind said piston according as said third valve is de-energized or energized, a first pressure responsive device connected with said cylinder at such point as to be subjected to the pressure in front of said piston when the piston is in its retracted position and to the pressure behind said piston when the piston has been moved away from its retracted position more than a predetermined distance, a second pressure responsive device connected with said cylinder at such point as to be constantly subjected to the pressure in front of said piston, a first and a second contact controlled by said first fluid pressure responsive device in such manner that said first contact will be closed when and only when the pressure to which said first device is subjected is below a predetermined pressure and that said second contact will be closed when and only when the pressure to which said first device is subjected is above a predetermined pressure which is higher than the pressure at which said first contact becomes closed, a third and a fourth contact controlled by said second fluid pressure responsive device in such manner that said third contact will be closed when and only when the pressure to which said second device is subjected is below a predetermined pressure which is less than the pressure at which said first contact becomes closed and that said fourth contact will be closed when and only when the pressure to which said second device is subjected is above a predetermined pressure which is equal to or less than the pressure at which said first contact becomes closed, a manually operable lever provided with a fifth and a sixth contact which are closed in one position of the lever and with a seventh contact which is closed in another position of the lever, an energizing circuit for said first valve including the fifth contact, a first circuit for said second valve including said second, fourth, and seventh contacts, a second circuit for said second valve including said first and seventh contacts, a first circuit for said third valve including said sixth contact, a second circuit for said third valve including said second, third, and seventh contacts, and car retarding means controlled by said piston. 5
8. Railway braking apparatus comprising a cylinder, a piston movable therein having a retracted and a projected position, means for at times admitting fluid to said cylinder in front of said piston to move it to its projected position, a first magnet valve effective when energized for admitting fluid behind said piston to move it to its projected position, a second magnet valve effective for exhausting fluid from behind or in front of said piston according as said valve is energized or deenergized, a first fluid pressure responsive device connected with said cylinder at such point as to be subjected to the pressure in front of said piston when the piston is in its retracted position and to the pressure behind said piston when the piston has been moved away from its retracted position more than a predetermined distance, a second pressure responsive device connected with said cylinder at such point as to be constantly subjected to the pressure in front of said piston, a first and a second contact controlled by said first fluid pressure responsive device in such manner that said first contact will be closed when and only when the pressure to which said first device is subjected is below a predetermined pressure and that said second contact will be closed when and only when the pressure to which said first device is subjected is above a predetermined pressure which is higher than the pressure at which said first contact becomes closed, a third and a fourth contact controlled by said second fluid pressure responsive device in such manner that said third contact will be closed when and only when the pressure to which said second device is subjected is below a predetermined pressure which is less than the pressure at which said first contact becomes closed and that said fourth contact will be closed when and only when the pressure to which said second device is subjected is above a predetermined pressure which is equal to or less than the pressure at which said first contact becomes closed, a first circuit for said first valve including said first contact, a second circuit for said first valve including said second and fourth contacts, a circuit for said second valve including said second and third contacts, and car retarding means controlled by said piston. 10 15 20 25 30 35 40 45 50
